UNITED STATES PATENT OFFICE.

EMMETT S. MILLER, OF CHICAGO, ILLINOIS.

MECHANISM FOR ACTUATING AND LOCKING ELEVATOR-DOORS.

1,265,804.

Specification of Letters Patent. Patented May 14, 1918.

Application filed December 3, 1917. Serial No. 205,120.

To all whom it may concern:

Be it known that I, EMMETT S. MILLER, a citizen of the United States, and a resident of the city of Chicago, county of Cook, 5 and State of Illinois, have invented certain new and useful Improvements in Mechanism for Actuating and Locking Elevator-Doors, of which the following is a specification.

10 My invention appertains to improvements in elevator controls and has special reference to mechanism for locking and releasing the doors upon elevator shafts and gates of elevator cars or cages, and for opening and 15 closing said doors and gates when unlocked.

Among the divers objects of my invention is the provision of mechanism adapted to open and close both or either the shaft door and the cage gate that can be operated to 20 open the door only when the cage has been stopped at a landing; pneumatic mechanism for cushioning the door and gate in their movements of opening and closing; and, in connection with means controlled by the operator for switching on the power to actuate 25 the door and gate, I have provided devices controlled by the door-operating mechanism for automatically cutting off the power for driving such mechanism at the end of each 30 opening and closing operation.

Further objects will be obvious to others after an understanding of my invention is had. I prefer to accomplish the divers objects by substantially the means and in the 35 manner hereinafter fully described and as more particularly pointed out in the claims, reference being now had to the accompanying drawings forming a portion of this specification, and in which similar reference 40 characters have been employed to designate the same parts throughout the divers figures.

In the drawings:

Figure 1 is a fragmental elevation, from the interior of the cage, of the upper portion 45 of the gate and door and the associated mechanism.

Fig. 2 is a front elevation of the mechanism located below the floor or platform of the cage for driving the door and gate opening and closing mechanism, together with the cushioning means and the devices for controlling the motive power.

Fig. 3 is a top plan of the mechanism illustrated in Fig. 2, with the floor or platform of the cage removed.

Fig. 4 is a fragmental plan of the means

for interlocking the shaft door with the slide for operating the door.

Fig. 5 is a similar view of this mechanism when the door is released. 60

Figs. 6 and 7 are, respectively, front and edge or end elevations of the yoke for connecting the operating mechanism with the cage gate.

Fig. 8 is a diagrammatic view in elevation, illustrating the cushioning and switch-controlling mechanism. 65

Fig. 9 is a similar view of this mechanism showing a different position of the relative parts. 70

Fig. 10 is a diagrammatic plan of the electrical switch and the circuit controlling the motor. 75

In the drawings the shaft is provided with the usual slidable door 1 at each floor 75 and the cage 2 is provided with a collapsible gate 3, that is adapted to slide upon a track 4, mounted over the doorway of the cage. Mounted upon the ends of the front wall of the cage are uprights 5, 5, to which the ends 80 of horizontally disposed parallel guide-rods 6, 6 are secured, that afford a track and support for a longitudinally reciprocable carriage 7, constructed in substantially the manner illustrated in detail in Figs. 6 and 85 7 of the drawings. Suitable apertures 8, 8 are made in a pair of upright lugs upon the lower members of the carriage, through which the hooked upper ends 10, 10 of a connecting yoke 9 are adapted to be passed, 90 in order to removably secure said yoke to said carriage. This yoke is Y-shaped, as shown, and its elongated member extends downwardly a distance sufficient to permit it to be securely bolted to one of the bars 95 comprising the collapsible gate, so that in the event of necessity arising to do so, the gate may be detached therefrom and opened independently of the mechanical operating means. 100

The mechanism for the control of the devices for actuating the doors of the shaft and the cage gate is preferably installed below the floor of the cage, and is illustrated in detail in Figs. 2, 3, 8, 9 and 10 of the 105 drawings. It comprises generally a belt for actuating the doors and gate, a motor for supplying the power, a specific form of transmission permitting the power to be applied in reverse directions, a novel switch 110 for controlling the motor, and devices for automatically disconnecting the power at the

end of each opening and closing operation. I have also supplied a cushioning device to eliminate the jar or impact when the doors or gate have finished their movements.

5 Taking up these instrumentalities in their order, I will first point out that these structures are mounted upon a shelf 54, hung from the lower surface of the platform of the cage by suitable brackets 55. Upon this 10 shelf, and conveniently adjacent to the walking-beam 50, is secured an electric motor, the shaft of which is provided with a pinion 57, meshing with an enlarged gear 58, mounted upon a shaft 59, journaled in the bearings in 15 the upper ends of vertically disposed brackets 60 and 61, mounted upon said shelf. As will be observed from Fig. 3, the bearing bracket 61 not only accommodates the end of shaft 59, but also is provided with a journal 62 20 positioned transversely to the journal for the shaft 59, which accommodates the transverse shaft 63. Rigidly secured to the transverse shaft 63, are a pair of facing friction disks 64, and mounted upon the shaft 59 is a 25 friction pulley 65. For greater rigidity, the transverse shaft 63 is provided with journals 67, located near the ends thereof, and upon the end of the transverse shaft 63, which extends beyond the journal 67, is provided a 30 pulley or sprocket 68, adapted to coöperate with the power belt or chain 69, to be herein-after described. Also rigidly secured to the shaft 63 is a collar 70, to which is pivoted the adjacent bifurcated end 71 of a bell-crank, the opposite end 71 whereof is 35 connected by means of a link 72 with the depending arm 73 of the T-shaped walking-beam 50. This walking beam 50 is pivoted intermediate its ends to a supporting bracket 40 51 pendent from the underside of the cage floor and is actuated by the depressing foot plungers 52 and 53 that are connected thereto and extend up through the floor of the cage within convenient reach of the conductor or operator, as shown in Fig. 2. The 45 shaft 63 has a slight longitudinal movement in its journals and by means of the mechanism just described is adapted to be moved to bring either of the friction disks 64 into 50 contact and coaction with the friction pulley 65, thereby securing the application of the power in either required direction.

The power belt or chain 69 passes around four pulleys or sprockets 73, located respectively in the corners of the front of the elevator cage, and the portion of said belt or chain that extends across the top of the cage is adjustably secured to the carriage or runner 7 by bolts 74. Alining with the lower 55 run of the power belt or chain and upon either side of the pulley or sprocket 68, are upright brackets 75, in the bifurcated upper portions of which are journaled anti-friction idlers or pulleys 76. The sprocket 68 extends below the upper edges of the idlers 76

and the power belt or chain 69, which runs over these idlers is thereby kept in dependable correlation with the under segment of said pulley or sprocket 68.

Mounted upon suitable brackets 77, which 70 may be conveniently located between the brackets 75, is a cushioning cylinder 78. The piston operating in said cylinder is secured to an elongated piston rod 79, extending through opposite ends of said cylinder and 75 having its outer ends supported in the brackets 80. Secured to and extending upwardly from opposite end portions of the piston rod 79 are adjustable arms 81, the upper ends of which are bifurcated or forked 80 to extend upon either side of the power belt or chain 69, and said belt or chain is provided with stops 82, which engage the respective arms 81 near the ends of the opening or closing movements of the door or 85 gate in order to secure the action of the cushioning cylinder 78.

Secured by means of a bracket plate 83 on the vertical wall of the shelf 54, is a double-acting electric-switch 84, that has one of 90 its terminals connected with one of the poles of the motor 56, through the wire 85, while its opposite terminal is connected with a suitable source of electric energy through wire 86. The opposite pole of the motor is likewise connected with the source of electric energy through wire 87. The switch 84 preferably comprises two separate axially alining cores 88 and 89, that are rotatably mounted within a suitable shell or casing of 100 insulating material, and said cores are respectively provided with transverse contact members 90 and 91, the former of which is adapted to be alternately brought into contact with its two pairs of binding posts *a a* 105 and *b b*, and the latter of which, being oppositely disposed, is adapted to be likewise brought into alternate contact with its respective two pairs of binding posts *y y* and *z z*. The cores extend through the ends of 110 the switch casing and the core 88 has a short arm 92, adjustably secured thereto, the lower end of said arm being connected through a link 93 to the lower portion of the arm 73 of the walking-beam. This permits 115 the switch arm 92 to be swung in one direction or the other by the depression of the respective foot plungers 52 and 53. In the same manner the extended end of core 89 is provided with an adjustable arm 94, to the 120 lower portion of which an actuating link 95 is connected, and the opposite end of said link is adjustably secured to and movable with an inverted U-shaped frame 96. The lower ends of the parallel members of frame 125 96 are provided with apertures to permit of the frame being loosely mounted upon the piston rod 79 between the upright arms 81 and the respective ends of the cushioning cylinder 78. When the piston rod 79 is be- 130

ing moved in either direction, by one of the stops 82 on the belt engaging its respective arm 81, the arm so engaged will, when it reaches the lateral member of the frame 96 5 nearest it, move said frame in the same direction with the piston rod 79, and thus rotate the core 89 into contact with the other pair of posts to break the circuit and stop the motor. This will occur only when the 10 door and gate have completed their opening or closing movement, and, when one of the foot plungers 52 or 53 has been depressed for the purpose of reversing the movement of the door and gate, the arm 73 of the 15 walking-beam will, through the link 93 and the arm 92, rotate the opposite core 88 of the switch to again make or close the circuit through the motor.

In order to move the shaft door 1 into an 20 opened or closed position after the same has been unlocked, I have provided said door with a suitable upright member 97, that is mounted upon the side of the door facing into the shaft and extending a suitable distance 25 vertically thereof. Pivotedly mounted upon the carriage 7 is a suitable horizontally disposed latch lever 98, the details whereof are illustrated in Figs. 4 and 5 of the drawings, said latch lever being pivoted adjacent 30 one end upon a bolt 99, secured in the carriage. The longer end of the latch lever is provided with a recess 99 in its outer portion, that is adapted to receive the upright member 97 of the door and the end of said 35 lever beyond this recess is curved or horn-shaped, as shown at 100 in Figs. 4 and 5, in order that this portion of the lever will ride over the upright member 97 when approaching the same. Said latch lever is 40 kept normally pressed toward the door 1 by a spring 101, that is mounted upon its pivoted bolt 99, so that accidental dislodgment is avoided. When the door has been closed by the movement of the carriage 7 45 and its connection through the latch lever 98 with the door, said latch lever is adapted to be disengaged by moving the outer portion thereof toward and between the guide rod 6 upon which the carriage slides. This 50 is done by providing a roller 102 upon the shorter end of the latch lever 97, that is adapted to engage the inclined track 103 carried by an adjustable sleeve 104, mounted upon one of the rods 6. Upon the roller 55 reaching the track 103, the latch lever 98 will be moved away from the door so that its recess 99 will be disengaged from the upright member 97 on said door and the cage 60 can be raised and lowered without striking said upright member.

What I claim is:—

1. In control mechanism for elevators, means for actuating the shaft door and cage gate comprising a reciprocable carriage 65 mounted upon the cage, means for detach-

ably securing the cage gate to said carriage, a latch mounted on said carriage and actuated by the movement thereof to engage and disengage said shaft door, a power belt connected to said carriage, a motor for actuating said belt, a compound switch interposed in the circuit of said motor, means for actuating one element of said switch, and devices carried by said power belt adapted to actuate the opposite switch element. 75

2. In control mechanism for elevators, means for actuating the shaft door and cage gate comprising a reciprocable carriage mounted upon the cage, means connecting the cage gate thereto, a device on said carriage adapted to engage the shaft door, a power belt connected to said carriage, a motor for actuating said belt, a compound switch interposed in the circuit of said motor, means for actuating one element of 80 said switch, and devices operated by the movement of said power belt adapted to actuate the opposite switch element. 85

3. In control mechanism for elevators, means for actuating the shaft door and cage gate comprising a reciprocable carriage mounted upon the cage, means connecting the cage gate thereto, a device on said carriage adapted to engage the shaft door, a power belt connected to said carriage, a 90 motor for actuating said belt, a compound switch interposed in the circuit of said motor, a rod connected to one of the movable elements of said switch, an actuating lever to which the opposite end of said rod 100 is connected, a rod connected to the opposite movable element of said switch, and means operated by the movement of said power belt adapted to move said last mentioned rod. 100

4. In control mechanism for elevators, means for actuating the shaft door and cage gate comprising a reciprocable carriage mounted upon the cage, means connecting the cage gate thereto, a device on said carriage adapted to engage the shaft door, a power belt connected to said carriage, a motor for actuating said belt, a compound switch interposed in the circuit of said motor, a rod connected to one of the movable elements of said switch, an actuating lever 115 to which the opposite end of said rod is connected, a rod connected to the opposite movable element of said switch, an intermittently movable device to which the last mentioned rod is connected, and means operated by the movement of said power belt adapted to reciprocate said intermittently movable device. 120

5. In control mechanism for elevators, means for actuating the shaft door and cage gate comprising a reciprocable carriage mounted upon the cage, means connecting the cage gate thereto, a device on said carriage adapted to engage the shaft door, a power belt connected to said carriage, a 125

motor for actuating said belt, a compound switch interposed in the circuit of said motor, a rod connected to one of the movable elements of said switch, an actuating lever to which the opposite end of said rod is connected, a rod connected to the opposite movable element of said switch, a reciprocable piston-rod actuated by the movement of said power belt, and a frame loosely carried by said piston-rod to which the last-mentioned rod is connected and adapted to be actuated at the end of each reciprocation of said piston-rod.

6. In control mechanism for elevators, means for actuating the shaft door and cage gate comprising a reciprocable carriage mounted upon the cage, means connecting the cage gate thereto, a device on said carriage adapted to engage the shaft door, a power belt connected to said carriage and having stops thereon, a motor for actuating said belt, a compound switch interposed in the circuit of said motor, a rod connected to one of the movable elements of said switch, an actuating lever to which the opposite end of said rod is connected, a rod connected to the opposite movable element of said switch, a reciprocable piston-rod, arms adjustable thereon and projecting from opposite portions thereof the upper ends of said arms adapted to be engaged by the stops carried by said power belt, and a U-shaped frame connected to said last-mentioned rod the parallel members of said frame being loosely mounted on said piston-rod and adapted to be engaged and moved by said arms while the latter are in engagement with said belt-stops.

7. In control mechanism for elevators, means for actuating the shaft door and cage gate comprising a reciprocable carriage mounted upon the cage, means connecting the cage gate thereto, a device on said carriage adapted to engage the shaft door, a power belt connected to said carriage, a motor, a power shaft provided with a pulley adapted to actuate said belt, transmission devices connecting said motor and power shaft including reversing mechanism, a compound switch interposed in the circuit of said motor, means for actuating one element of said switch, and devices operated

by the movement of said power belt adapted to actuate the opposite switch element.

8. In control mechanism for elevators, means for actuating the shaft door and cage gate comprising a reciprocable carriage mounted upon the cage, means connecting the cage gate thereto, a device on said carriage adapted to engage the shaft door, a power belt connected to said carriage, a motor, a power-shaft provided with a pulley adapted to actuate said belt, transmission devices connecting said motor and power shaft including reversing mechanism, devices on the elevator cage for operating said reversing mechanism, a compound switch interposed in the circuit of said motor, means for actuating one element of said switch, including a rod actuated by said devices for operating the reversing mechanism, and devices operated by the movement of said power belt adapted to actuate the opposite switch element.

9. In control mechanism for elevators, means for cushioning the movements of the shaft door and cage gate comprising a cylinder and piston therefor, a piston rod extended through opposite ends of said cylinder, upright arms adjustably carried upon the opposite end portions of said piston rod, a power belt adapted to be moved in opposite directions to actuate the shaft door and cage gate, and stops on said belt adapted to engage and move said arms during the latter portion of each movement of said belt.

10. In control mechanism for elevators, means for cushioning the movements of the shaft door and cage gate comprising a cylinder and piston therefor, a piston rod extended through opposite ends of said cylinder, a reciprocating device adapted to actuate the door and gate, and members carried by opposite portions of said piston rod adapted to be engaged by said reciprocating device whereby said piston rod is moved in opposite directions.

Signed at Chicago, county of Cook and State of Illinois, this 28th day of November, 1917.
